UNITED STATES PATENT OFFICE.

SAMUEL B. STEWART, JR., OF SCHENECTADY, NEW YORK, ASSIGNOR TO
GENERAL ELECTRIC COMPANY, A CORPORATION OF NEW YORK.

ICE-CUTTER FOR THIRD-RAIL ELECTRIC RAILWAYS.

SPECIFICATION forming part of Letters Patent No. 758,153, dated April 26, 1904.

Application filed September 20, 1901. Serial No. 75,798. (No model.)

To all whom it may concern:

Be it known that I, SAMUEL B. STEWART, Jr., a citizen of the United States, residing at Schenectady, in the county of Schenectady and State of New York, have invented certain new and useful Improvements in Ice-Cutters for Third-Rail Electric Railways, of which the following is a specification.

This invention relates to third-rail electric railways in which the working conductor is a third rail laid parallel with and adjacent to the track-rails and supplying current to the motors on the cars through a shoe carried on the car and sliding on the top or upper surface of the third rail. It is essential that a good contact be maintained between this shoe and the rail; but as the rail is usually exposed to the weather it is liable to become coated with ice in the winter.

My invention aims to provide means for removing the ice from the top of the rail; and to this end it consists in a device mounted on the car preferably near to and in advance of the trolley-shoe and serving to crack up and scrape off the ice as the car moves along.

In the drawings, Figure 1 is a side view of a car-truck equipped with my invention. Fig. 2 is a top plan sectional view of the ice-scaper on an enlarged scale. Fig. 3 is a sectional end view of the same.

The truck A is of the usual construction, having on one side a beam B, on which is supported the trolley-shoe C, resting and sliding on the third rail D, which is preferably an ordinary railway-rail supported on insulators E.

Secured to the beam B is a bar F, of wood or other insulation, from which depend two parallel U-shaped hangers G, between which are journaled one or more cutting-wheels H.

The journals h have some vertical play in upright slots g in the hangers, so that the wheels can rest on the third rail and rise and fall with any slight irregularities of the track. The wheels are wide enough to extend entirely across the tread of the rail irrespective of the lateral play of the truck. They are solid and heavy, and their peripheries are provided with sharp teeth preferably diagonal to the axis of the wheel, as shown. The weight of

the wheels causes these teeth to cut into and crack up the coating of ice on the rail. This effect is heightened by running the diagonal lines on the wheels in different directions, as shown in Fig. 2, so that the cuts made by one wheel cross those made by the other. To remove the broken ice, one or more scrapers are arranged adjacent to the cutting-wheels. These are preferably sharp blades I, set diagonally to the rail, so as not to catch in the rail-joints, and carried in swinging frames K, pivoted to the hangers G preferably on the extended journals of the wheel-shafts. Stoppins g' just above the inner ends of the frames prevent them from dropping too far. The blades rest on the third rail and scrape off to one side the pieces of ice broken up by the cutting-wheels. By using two scrapers—one before and one behind the cutting-wheels—the device will work equally well when running in either direction.

My invention provides a simple and efficient means for keeping the third rail clear of ice and snow and insures a good contact for the trolley-shoe.

What I claim as new, and desire to secure by Letters Patent of the United States, is—

1. The combination with a motor-truck for a third-rail electric railway, of two ice-breaking wheels having diagonal teeth adapted to engage the third rail, the teeth on one wheel running in a different direction from those on the other wheel.

2. The combination with a motor-truck, of a beam carrying a third-rail trolley-shoe, insulated hangers depending from said beam, and having upright slots, and one or more ice-breaking wheels having their journals received in said slots.

3. The combination with a motor-truck, of a beam carrying a third-rail trolley-shoe, insulated hangers depending from said beam independent of the means for attaching the trolley-shoe to said beam, and frames pivoted to said hangers and carrying scraping-blades.

4. The combination with a motor-truck for a third-rail electric railway, of ice-breaking wheels carried by said truck and having a vertical play relative to said truck, and a frame

- pivottally supported on said truck and carrying a blade set diagonally to the third rail.
5. The combination with a motor-truck for a third-rail electric railway, of hangers insulated from said truck, ice-breaking wheels journaled in said hangers and adapted to break the ice from the upper surface of the third rail, and pivotally-mounted scraping-blades adjacent to said wheels.
10. 6. The combination with a motor-truck for a third-rail electric railway, of hangers insulated from said truck, ice-breaking wheels journaled in said hangers and having vertical play, frames pivoted on the journals of said 15 wheels, and scraping-blades in said frames set diagonally to the third rail.
20. 7. The combination with a motor-truck for a third-rail electric railway, of hangers carried by said truck, ice-breaking wheels journaled in said hangers said wheels having toothed peripheries adapted to engage the upper surface of the third rail, and scrapers adjacent to said wheels.
25. 8. The combination with a motor-truck for a third-rail electric railway, of ice-breaking wheels supported from said truck said wheels
- having toothed peripheries adapted to engage the upper surface of the third rail, and scrapers for removing from the third rail the ice broken by the said wheels independent of the direction of movement of said truck. 30
9. The combination with a car-truck for a third-rail electric railway, of two ice-breaking wheels having diagonal teeth adapted to engage the entire upper surface of the third rail the teeth of one wheel running in a different direction from those on the other wheel, and scrapers for removing from said third rail the ice broken by said wheels independent of the direction of movement of the said truck. 35
10. As a means for removing ice or sleet from electric-railway third rails, a pressure-roller carried by the moving vehicle and traveling on the third rail, said roller having corrugations on its periphery at an angle to said 40 periphery.

In witness whereof I have hereunto set my hand this 16th day of September, 1901.

SAMUEL B. STEWART, JR.
